US0D1037825S

(12) **United States Design Patent** (10) Patent No.: **US D1,037,825 S**
(45) Date of Patent: ** Aug. 6, 2024

(54) **LOCK**

(71) Applicant: **Ningbo Eudemon Child Protective Equipment Co., Ltd.**, Ningbo (CN)

(72) Inventors: **Binhui Li**, Ningbo (CN); **Yingfeng Chen**, Ningbo (CN)

(**) Term: **15 Years**

(21) Appl. No.: **35/515,813**

(22) Filed: **Dec. 8, 2022**

(80) **Hague Agreement Data**

Int. Filing Date: **Dec. 8, 2022**

Int. Reg. No.: **DM/225517**

Int. Reg. Date: **Dec. 8, 2022**

Int. Reg. Pub. Date: **Dec. 23, 2022**

(51) **LOC (14) Cl. 08-07**

(52) **U.S. Cl.**

USPC **D8/333**; D8/339

(58) **Field of Classification Search**

USPC D8/44, 330-334, 339-343, 346, 349, D8/354-356, 359, 383

CPC E05B 67/063; E05B 67/22; E05B 67/06
